Application May 6, 1953, Serial No. 353,274

3 Claims. (Cl. 240—11.3)

The present invention relates to a lighting unit safe for use in a zone which may contain an explosive or inflammable atmosphere, such as oil or gasoline tanks, mines, chemical plants, etc.

In zones containing inflammable or explosive materials or atmosphere, the use of a conventional lighting unit, susceptible as it is to sparking, arcing, short-circuiting, overheating or breaking, constitutes a dangerous hazard. In such a lighting unit, the main sources of fire and explosion hazard are the light, the wires and the switch.

The object of the present invention is to provide a new and improved complete portable lighting unit or device with wire connections, which device is safe for use in a fire and/or explosion-hazardous zone and which meets the most rigid requirement of security in this respect.

In accordance with certain features of the invention, the portable lighting device comprises a lighting fixture and a control box therefor. The lighting fixture constitutes a sealed chamber which encloses a source of light, such as an incandescent lamp, and which has a light permeable wall section; and the control box comprises a pressure chamber with an inlet connection for delivering a non-combustible gas thereto, such as carbon dioxide under pressure, or air under considerable pressure, an automatic switch in the circuit with the lamp and responsive to the pressure in said pressure chamber and operable into position to open the lamp circuit, when the pressure in said pressure chamber drops below a predetermined value, and a junction or terminal station for the leads of said circuit.

The lighting fixture and the control box are interconnected by a flexible conduit extending between the pressure chamber and the lamp-enclosing chamber and establishing pressure communication between said chambers to maintain the lamp in the latter chamber in an envelope of incombustible gas under superatmospheric pressure. This flexible conduit also serves as a shield for the electric wire connections from the junction station to the lamp.

The conduit which connects the lighting fixture with the control unit or box, is preferably flexible, and may be of any suitable structure that will withstand pressures from within without leakage of air or gas under greater pressure than atmospheric pressure. Preferably an inert gas is employed with this safety lighting unit. This improved conduit carries within it the electrical wiring connections between the control unit and the light or lamp. This makes a complete connection safe from explosions between the lighting fixture and the control unit wherein there is gas under pressure in the connection and within the lighting fixture and within the control unit.

Heretofore in connections between a lighting unit and a far removed electrical supply, the ordinary wire cord is used and is subject to having its exterior insulating surface cut, scratched or broken by reason of being flexed or moved around and over mechanical or steel structures,

2

or the like. With the use of a portable light, these prior connecting cords are soon damaged, cut or broken and consequently a defective wiring develops. Therefore, this prior type of connecting cord is not acceptable in connecting the control unit to the lighting fixture shown herein, and, therefore, it becomes very desirable to have the wire connections carried within the preferred type of conduit herein disclosed. If for any reason the electrical cord or wire connections within the conduit become broken or are defective in any manner, explosion from sparks will not take place as there is the inert gas around the electrical connecting cord or wiring and the gas pressure is greater than the surrounding atmospheric pressure. Such a safety situation is not true when the ordinary wiring connecting cord is employed between a lamp itself and its electrical supply.

In a desired form of flexible conduit employed herein between the lighting fixture and the control unit or box, it is desirable to employ a conduit made of flexible metal, or a satisfactory neoprene material, or a flexible plastic conduit which preferably carries a neoprene coated electrical cord, or the conduit may be made of a combination of several of the noted materials.

By means of the arrangement described, the lighting fixture is free from switches or similar control devices, which might spark or otherwise constitute a source of danger from fire or explosion, and the lamp, which might also constitute a source of such danger, is protectively enveloped in a blanket of incombustible or incombustible gas under pressure. The pressure in the sealed light chamber prevents any of the surrounding hazardous atmosphere at lower pressure from leaking into said chamber, thereby preventing this contaminating atmosphere from coming into contact with a fire or explosion-generating source in said fixture. If for any reason, the inert gas under pressure in the light chamber should leak out or escape or the walls of the light fixture should break, causing the pressure of the gas in said chamber to fall below a safe limit, the switch in the control box will automatically open, thereby opening both lead wires of the circuit of the lamp and rendering at the control box the circuit harmless.

Since the control box is isolated from the lighting fixture, and is attached thereto solely through the flexible connection therebetween, this control box, in operation, can be placed in a safe remote position with respect to the lighting fixture and outside of the hazardous zone. The control box of the lighting unit, therefore, does not constitute a fire or explosion hazard when so positioned.

Because the sealed flexible conduit containing the wires between the control box and the source of light is maintained under the pressure of the inert or incombustible gas, the surrounding hazardous atmosphere is prevented from passing thereto just as in the case of the light chamber, thereby eliminating the possibility of an explosion or fire due to any short-circuiting, arcing, or overheating of these wires.

The pressure gas in the flexible conduit serves not only the purpose described but also as a means for preventing the dangerous overheating of the parts by convection, and the walls of said conduit aid by conduction and radiation, to prevent such overheating.

Various other objects, features and advantages of the invention are apparent from the following particular description and from an inspection of the accompanying drawings, in which

Fig. 1 is a section somewhat diagrammatic, showing one way in which a lighting device embodying the present invention may be used;

Fig. 2 is a vertical section through the lighting fixture

forming part of the lighting device of the present invention;

Fig. 3 is a detail section of the lighting fixture taken along the lines 3—3 of Fig. 2 but on a larger scale;

Fig. 4 is a detail section of the lighting fixture taken along the lines 4—4 of Fig. 2 but on a larger scale;

Fig. 5 is a side elevation of the control box forming another part of the complete lighting device of the present invention;

Fig. 6 is a section of the control box taken along the lines 6—6 of Fig. 5;

Fig. 7 is an end view of the control box shown with the end cover removed;

Fig. 8 is a section of the control box taken along the lines 8—8 of Fig. 6; and

Fig. 9 is a wiring diagram for the electric circuit.

Referring to Fig. 1 of the drawings, the complete lighting unit or device embodying the present invention is of the portable type with outside wire connections to a source of supply, and comprises a lighting fixture 10, a control box 11, and a flexible conduit connection 12 therebetween. The lighting fixture 10 comprises an opaque hood 13 (Fig. 2) made of safe materials, such as aluminum of desired thickness combined with other materials, and having a lower skirt 14 formed with an internal light-reflecting surface 15. The materials should be of the "compatible" type, i. e., those that will not create a difference in electrical potential that would result in sparking. Such materials are aluminum and bronze, for example. Across the lower end of this hood 13 is a light permeable wall member 16 in the form of a lens of high impact heat resistant material, such as Pyrex glass, forming with the hood 13 a light chamber 17. This chamber 17 is hermetically sealed by any suitable means. In the specific form shown, the rim of the skirt 14 has a seating flange 18 and the lens 16 has an annular edge 20 embraced by a sealing gasket 21 and sealably clamped against said seating flange by a ring 22 secured to said skirt by studs 23.

Supported in the sealed light chamber 17 is a suitable source 25 of electric light shown in the form of a conventional incandescent lamp. This lamp 25 is resiliently supported in the light chamber, and for that purpose, the upper part of the hood 13 has a pair of oppositely disposed bosses 26 mounting a socket strap 27 by means of screws 28. An approved lamp socket 29 into which the lamp 25 is screwed is shown with a base 30 of Bakelite or any other suitable safe material and is resiliently supported on the strap 27 by means of a socket spring 31 in the form of a ring. This socket spring 31 is secured at diametrically opposite sections to the strap 27 by two bolts 32 and rigidly secured to the socket base 30 by means of two bolts 33 quadrantly arranged with respect to the bolts 32 and passing through notches 34 in said socket base. This spring 31, being flexible and the socket base 30 being fastened opposite the two bolts 32, will permit the lamp 25 to oscillate to some extent whenever the lighting fixture 10 bumps against any object. Thus, there is enough flexibility in the mounting of the lamp 25 to absorb shocks so that it will not be broken or loosened in its socket even though the fixture 10 be subject to relatively heavy shocks. Also, with this type of flexible mounting, the danger of defective wiring or looseness of the lamp in its socket is reduced to a minimum.

The lamp socket base 30 carries two screws 36 serving as binding posts for two insulated wires 37 and 38 and one of the bolts 28 mounted on the strap serves as a binding post for an insulated ground wire 41. These wires 37, 38 and 41 lead into the lighting fixture in a manner to be described.

The hood 13 has a pair of external rings 42 on the top, serving as a means for suspending the lighting fixture 10, if desired, or for directing the lighting fixture to any part of a zone through a cable or rope tied or otherwise attached thereto.

The control box 11 comprises a pressure chamber housing 50 (Figs. 6 and 8) of rectangular cross-section and an explosion-proof housing 51 preferably of similar rectangular cross-section, made of safe material, such as aluminum, and connected together by means of bolts 52 passing through respective confronting flanges 53 extending outwardly from the housing. The metal to metal flange engagement constitutes an explosion-proof joint that is acceptable under the Underwriters code. The pressure chamber housing 50 is formed with a partition 54 dividing said housing into two compartment chambers 55 and 56.

The compartment chamber 55 is closed at its outer end by a cover plate 57 secured to the housing 50 by studs 58, and the compartment chamber 56 is hermetically sealed by a rectangular plate 60, serving as a partition between the latter chamber and a switch chamber 61 defined by the explosion-proof housing 51. This plate 60 is supported against a flange 62 extending inwardly and rectangularly from the inner end of the pressure chamber housing 50, and is secured to said plate by means of studs 63 threaded into inserts 64 fitted into holes in said flange. A rectangular gasket 65 between the plate 60 and the flange 62 serves to seal hermetically the junction between said plate and said flange when studs 63 are tightened down, so that the chamber 56 is hermetically sealed and can be maintained under gas pressure, as will be described hereinafter, while the adjoining chamber 61 is not hermetically sealed but is explosion-proof.

The chamber 56 is maintained under pressure by means of a non-combustible or non-inflammable gas, preferably carbon dioxide. The gas is introduced into the pressure chamber 56 through a pressure valve 66, Figs. 6 and 7, which is mounted on the partition wall 54, and which may be of the conventional type employed in automobile or bicycle tires. This valve 66 has its outlet end extending into the pressure chamber 56 and its inlet end projecting into the chamber 55.

To maintain the gas pressure in the chamber 56, below a predetermined maximum, there is provided a suitable relief valve 67 mounted in the partition wall 54 and having its inlet extending into the pressure chamber 56 and its outlet as well as the main body of the valve projecting into the chamber 55. The chamber 55 is not hermetically sealed, so that this chamber is maintained under atmospheric pressure, which does not interfere with the relief of excess pressure through the relief valve 67.

The chamber 55 enclosing the main bodies of the inlet pressure valve 66 and the relief valve 67 protects these valves against possible breakage or injury. Access to either of these valves 66 or 67 is easily gained by removal of the cover plate 57.

Connecting into one end of the pressure chamber 56 is one end of the flexible conduit connection 12, the other end of which connects into the lighting fixture 10. This connection 12 is long enough to permit the control box 11 to be placed outside of a hazardous location while the lighting fixture 10 is operating in said location, and comprises a sealed flexible conduit serving not only as a means for establishing and maintaining pressure gas communication between the pressure chamber 56 and the light chamber 17, but also as a cable for the wire connections 37, 38 and 41 between the control box 11 and the lighting fixture 10. The connection 12 for this purpose preferably comprises a cable connector 70 at one end sealably fitted into the end wall of the pressure chamber 56, a flexible armour tubing 71 of any suitable construction, preferably as conventional copper and bronze construction, secured at one end to said cable connector and shown formed with an inner pipe 72 crimped for flexibility and an outer protective braided sheathing 73. The other end of this flexible tubing 71 is secured to a tube fitting 74 threaded into a stainless steel insert 75 in the top of the hood 13.

When the pressure of the gas in the light chamber 17 of the light fixture 10 drops below a predetermined safe

value, the circuit of the lamp 25 is automatically shut down by the opening of the switch in the pressure chamber in the control box. The means for accomplishing this operation comprises a suitable pressure switch 76 in the chamber 61 responsive to the pressure of the gas in the chamber 56, and operable into circuit-closing position when the pressure in the chamber 56 rises above an operable set limit, and into circuit-opening position when the pressure in said chamber 56 drops below a lower safety limit. This pressure switch 76 is shown of the conventional snap type having spring-pressed bellows in a casing 77 and a switch mechanism in a casing 78, operated by the expansion and contraction of said bellows into open and closed position. The pressure switch 76 is mounted on the mounting plate 60 with the inlet 79 of the bellows threaded into said plate for communication with the chamber 56. The outside of the bellows in the casing 77 is under atmospheric pressure, so that a pressure in the inside of the bellows corresponding to the pressure increase in the chamber 56, causes the bellows to expand and when the pressure in the chamber 56 rises to a predetermined upper value, the switch mechanism in the casing 78 snaps closed, assuming that the switch was opened. Any decrease in the pressure in the inside of the bellows corresponding to a decrease in the pressure in the chamber 56 causes the bellows to contract, and when this pressure falls to a predetermined lower value, the switch mechanism in the casing 78 snaps open.

The control box 11 serves not only for the functions described, but also as a junction box for the current wires 37 and 38 of the lamp circuit and for the ground wire 41. For that purpose, connected to the side wall of the housing 51 is an explosion-proof portable cord connector 80, by which insulated wires 37a, 38a and 41a are led into the chamber 61 of said housing through a cable 81 having means for connection to a current feed and ground outlet. In the chamber 61, the current feed wires 37a and 38a are connected to two contacts of the pressure switch 76, as noted in Fig. 9. Two terminals of the pressure switch 76 have current wires 37b and 38b connected thereto and to the binding posts 82 of an explosion-proof connector 83 screwed into the plate 60, see Fig. 8. Also secured to one of these binding posts 82 in the chamber 61 is the ground wire 41a.

The binding posts 82 in the connector 83 extend into the pressure chamber 56 and the current lines 37 and 38 and the ground line 41 in said chamber connect into their corresponding binding posts 82. The circuit of the lamp 25 thereby extends through the control box 11 and through the lighting fixture 10 and is automatically rendered either operative or inoperative by the switch 76 in series with said lamp.

The control box 11 is portable and can be conveniently carried from place to place. To that end, the two housings 50 and 51 have respective ears 85 to which are pivotally connected the ends of a U-shaped handle 86. The confronting flanges 53 are provided with recesses 87 to permit the handle 86 to nest compactly therein when not in use.

In the operation of the complete lighting device, this device is first prepared for use by filling the pressure chamber 56 and consequently the other spaces and chambers of said device in communication therewith with carbon dioxide, or air under considerable pressure through the inlet pressure valve 66, while the cover plate 57 is removed to permit access to said inlet valve in the chamber 55. This carbon dioxide is delivered to the inlet pressure valve 66, as for example from a cartridge, and enough is delivered to cause the relief valve 67 to blow according to the setting of said relief valve. For example, the relief valve 67 may be set at 20 p. s. i. so that when the pressure in the chamber 56 reaches that value, said valve will automatically open to discharge the excess carbon dioxide. After the cover plate 57 is restored in position, the lighting device is ready for use.

In any mode of use, the lighting device may be carried to the location of use, and the lighting fixture 10 positioned in the zone containing the hazardous atmosphere of explosive or combustible nature, while the control box 11 is set at a safe remote distance from said atmosphere. In Fig. 1 there is shown, for purposes of illustration, one possible mode of application; although it must be understood that the lighting unit or device of the present invention is applicable to other situations where a hazardous atmosphere does or may exist. In the illustrated use, the lighting fixture 10 is lowered into a tank 9 which contains oil, gasoline or other chemicals of an explosive or combustible nature, or which previously contained such materials and still retains some of the dangerous fumes therefrom. While the lighting fixture 10 is lowered into this hazardous location, the control box 11 through the long flexible conduit connection 12 is maintained outside this location and away from any dangerous or highly explosive gases.

Since the pressure in the chamber 56 is initially at a maximum, above the closing limit of the pressure switch 76, this switch is closed and the circuit of the lamp 25 will be closed whenever the cord or cable 81 is connected to a suitable outlet or to a source of current and to a ground connection, thereby causing the lamp 25 to light up. This pressure switch 76, for example, may be set to kick into closed position, when the pressure in the chamber 56 rises above 10 p. s. i. and may be set to kick out into open position when the pressure in said chamber drops below 7 p. s. i.

Since the chamber 17 containing the lamp 25 is under the pressure of the inert gas, this pressure keeps out any contaminating hazardous gases from leaking into said chamber. Also, since the flexible connection 12 is under the same pressure, the contaminating hazardous gases are also kept out of said connection. Therefore, in case of short-circuits, arcing or overheating of the lamp 25 or of the wires 37 and 38, no explosion or fire will take place in the presence of the inert carbon dioxide. Moreover, overheating of the parts of the lighting device, due to the heat generated by the incandescent filament of the lamp 25, is not apt to occur, since the heat is dissipated from the vicinity of the lamp 25 by convection currents created in the gas in the chamber 17 and in the chamber of the flexible connector 12, by conduction to the metal parts of the chamber 17 and the connector 12 and by radiation from the external surfaces presented by said parts.

In case of leakage of the gas from the lighting device to an extent sufficient to drop the pressure of said gas to a dangerous point, some of the contaminating atmosphere might pass into the chamber 17 of the lighting fixture 10 and into the flexible connector 12, thereby creating a hazardous condition in the presence of a live circuit. However, the drop in pressure of the carbon dioxide in the chamber 56 below a predetermined value automatically opens the switch 76 in the control box 11, so that the wires 37 and 38 are no longer live wires, and the lamp 25 is no longer lit. Under these conditions, any leakage of the contaminating gases into contact with internal parts of the lighting fixture 10 and the flexible connector 12 will not create a fire or explosion hazard.

If the pressure of the carbon dioxide in the pressure chamber 56 should be reestablished beyond the upper limits, so that the lighting device is again safe for use in a hazardous location, then the pressure valve 76 will automatically close, thereby closing the circuit of the lamp 25, assuming that the inlet wire connections are plugged into a current feed source.

In the foregoing description, it will be noted that the inert gas is introduced through valve 66 into pressure chamber 56 by a suitable means, such as a pump, or it may be introduced through a valve pipe leading from a supply, or, if desired, a small bomb containing the gas under pressure could be screwed in to the valve 66 and 75 be punctured after being moved to a predetermined posi-

tion in relation to the valve. Other types of bombs could be employed for introducing an inert gas.

It will be noted further from the general description herein that an improved and novel safety device or unit has been provided wherein the switching arrangement governing or controlling the lamp 25 is readily positioned away from any explosive gases even though the light itself in the fixture 10 is needed within the area where explosive gases are present. Also, it will be noted that the inert gas extends from the control unit to the lighting fixture and surrounds the lamp 25 and any structures where there would be possibilities of sparks due to bad or defective electrical connections. This pressure is a pound per square inch greater than atmosphere pressure into which the lighting fixture may be inserted or lowered. Thus, any explosive gases would not enter the fixture or come close to any of the electrical connections, thereby making it quite impossible to have any explosions due to this improved apparatus when positioned to light the inside of a container or a bulkhead or other area which may contain explosive gases.

In addition to the above advantageous features, the structure of the apparatus herein and its division into a fixture, and a controlling unit, and the conduit between them, the strength of the apparatus employed and the ability to dissipate heat created by the lamp, meets the Underwriter's requirements. With such an improved safety lighting unit or device, it now becomes possible to light the inside of a container or area in a manner not heretofore possible due to possible explosions, and with such an improved light, it is now possible to complete the desired cleaning of the interior of the container or area in an efficient manner.

While the invention has been described with particular reference to a specific embodiment, it is to be understood that it is not to be limited thereto but is to be construed broadly and restricted solely by the scope of the appended claims.

The invention claimed is:

1. A lighting device safe for use in fire and explosion hazardous locations, comprising an electric lighting circuit, a lighting fixture containing a light chamber, a control box containing an explosion-proof chamber and a pressure chamber and a pressure responsive switch in said circuit located in said explosion-proof chamber and having a pressure responsive element in communication with said pressure chamber for operating the switch mechanism forming part of said switch, an inlet valve connecting into said pressure chamber for feeding a charge of incombustible gas under pressure into said pressure chamber, and a relief valve connecting into said pressure chamber for limiting the maximum pressure of the gas charge in said pressure chamber, said circuit including an electric cord having one end connecting into said explosion-proof chamber and the other end adapted to be connected to a current feed station, and a flexible conduit extending between said fixture and said control box to contain the wires for said circuit and establishing pressure communication between said light chamber and said pressure chamber, said pressure responsive switch being operable to open said circuit automatically when the pressure in said pressure chamber drops below a predetermined value, said control box comprises a chamber for housing the major portions of said valves, the latter chamber having a cover plate removable to permit access to said valves, said pressure chamber being located between said explosion-proof chamber and the chamber housing the major portions of said valves.

2. A lighting device safe for use in fire and explosion hazardous locations, comprising an electric lighting circuit, a lighting fixture containing a light chamber, a

control box comprising a pressure chamber housing and an explosion-proof housing connected end to end, said explosion-proof housing defining a pressure switch chamber, said pressure chamber housing having a partition dividing the latter housing into two compartment chambers, one of which constitutes a pressure chamber and the other a valve chamber, an inlet pressure valve connected into said partition and accessible from said valve chamber to permit a charge of incombustible gas under pressure to be fed into said pressure chamber, a relief valve connected into said partition and extending into said valve chamber to maintain the pressure in said pressure chamber below a predetermined maximum, a removable cover plate for said valve chamber, a removable plate serving as a partition between said pressure chamber and said pressure switch chamber and hermetically sealing said pressure chamber from said pressure switch chamber, a pressure responsive switch in said pressure switch chamber having a pressure responsive element in communication with the pressure in said pressure chamber, a connector secured to said explosion-proof housing and adapted to lead current wires in said circuit from a current feed station to the interior of said pressure switch chamber for connection to said pressure responsive switch, and a connector secured to said partition plate and having binding posts in said pressure switch chamber for the current wires of said circuit leading from said pressure responsive switch and having binding posts in said pressure chamber for the current wires of said circuit leading to said lighting fixture, and a flexible conduit secured at its ends to said light chamber and said pressure chamber to establish pressure communication between said light chamber and said pressure chamber and serving as a conduit for the current wires of said circuit extending between said pressure chamber and said lighting fixture.

3. In a complete lighting device where part of it is subjected to explosive gases, the combination of a portable control box capable of being positioned away from explosive gases, a lighting fixture with a lamp therein capable of being positioned in a chamber where explosive gases exist, a conduit connecting said control box and said lighting fixture and carrying light supplying means to said lamp, said conduit being flexible and substantially leakproof to any gases and during operation having gases under pressure therein, said portable control box comprising a chamber for housing a switch automatically opened but closable under gas pressure and having an electrical inlet for power supply lines, said lines being sealed in the conduit leading into said control box, said lines leading to the switch and leading to a second chamber, the lines leading to the second chamber being sealed to prevent gases from passing from one chamber to the second chamber, said lines passing from said second chamber to said lighting fixture for lighting said lamp, and a third chamber in said control box having a gas inlet valve, and an outlet valve for controlling gas under pressure into said first and said second chambers and for preventing pressures from rising more than a maximum amount in said first and second chambers.
